UNITED STATES PATENT OFFICE.

SAMUEL DIGGS BLAKE, OF DALLAS, TEXAS.

DRAWERS AND PANTALOONS.

SPECIFICATION forming part of Letters Patent No. 321,416, dated July 7, 1885.

Application filed July 19, 1884. (Model.)

To all whom it may concern

Be it known that I, SAMUEL DIGGS BLAKE, of Dallas, in the State of Texas, have invented certain Improvements in Drawers and Pantaloons, of which the following is a specification.

The aim of this invention is to produce from the minimum amount of material and with a slight expenditure of labor drawers and pantaloons possessing great strength and durability and adapted to be worn without discomfort.

To this end it consists in the drawers formed of two pieces cut in the peculiar form and united in the peculiar manner hereinafter described.

Referring to the accompanying drawings, Figures 1 and 2 are face views of the two blanks or patterns employed in the construction of my drawers. Fig. 3 is a perspective view of a finished garment, the front being open in order to expose to view the internal portion. Fig. 4 is a cross-section of one of the legs, showing the re-enforced seam on the inside of the leg. Fig. 5 is a vertical central section through the garment from front to rear.

In proceeding to manufacture my garment I provide the two blanks or patterns A and B, duplicates of each other, except that they are "rights and lefts."

Referring to the blank A, it will be seen that it resembles in its general outline the patterns now in common use, but differs therefrom in that it has on the rear edge a flap or extension, *c*, designed to assist in re-enforcing the seat, and also an extension, *d*, extending downward from the crotch to the lower end of the leg, and designed to overlap the opposite edge of the leg portion for the purpose of giving a re-enforced or double thickness at the leg-seam. On the opposite edge the blank A is cut with an extension, *e*, extending from the crotch to the lower end of the leg, and designed to co-operate with the extension *d* at the opposite side.

The lines on which the leg is stitched together are represented by dotted lines, which indicate the outline of the patterns in common use.

That portion of the blank outside of the dotted lines is the portion to which my improvement relates. At its lower end the blank is

provided near each edge with a slit or incision, *f*, so that when these slit portions are lapped and stitched together with the two slits in line a solid or seamless gore or incision will be formed in the lower part of the leg.

As before mentioned, the blank B is in all respects similar to the blank A, except that it is adapted for the right instead of the left side of the garment. Each blank is designed to form the whole of one side or leg of the garment complete.

In making use of the blanks I fold or double each blank lengthwise through the middle, as represented by the dotted line *i*,lapping or folding the opposite edges *d* and *e* of its leg portion upon each other to the extent indicated by the dotted lines. I then complete each leg portion by running two lines of stitching along the edges of the overlapped portion, as shown at *l l'*, Fig. 5. In this manner I produce a leg having on the inside a double thickness of cloth, but having, instead of the usual heavy seam or welt, a flat surface, which may be worn without discomfort. Around the slits or incisions *f* at the lower edge I run one or more lines of stitching, and, if desired, hem the edges. When thus finished, the garment presents a seam having a double thickness of fabric at its ends and on both sides and without a seam at its ends. Being thus constructed, the garment is free from the usual liability to rip at the edge of the incision.

Having thus prepared the two blanks, I bring them together and join their front and rear edges, overlapping the flaps *c* at the back in such manner as to produce a seat of double thickness, commonly known as a "re-enforced" seat. I also lap or fold the flaps *g* upon each other to the extent represented by the dotted lines, thus producing a crotch of double thickness and without a center seam, as usual. The garment will be provided with the usual waistband, and, if desired, with the usual facings at the front; or it may be otherwise finished as desired, my invention having reference only to the manner of constructing and joining the parts which form the seat, the crotch, and the legs.

I am aware that it is not new to use blanks with overlapping seat portions.

I am also aware that overlapping points or flaps have been used in the crotch portion of drawers. I believe myself, however, to be the first to construct a garment composed of but 5 two pieces so constructed and united as to produce the double seat, the double seamless crotch, and the legs of a double thickness on the inside.

Having thus described my invention, what 10 I claim is—

1. A pair of pantaloons, each leg of which is composed of a single piece, having extended portions *c*, *g*, *d*, and *e*, as described, overlapped and united by two lines of stitching, as de- 15 scribed.

2. A pair of pantaloons, each leg of which is composed of a single piece, having the two edges *d* and *e* extended from the crotch to the foot of the leg, said extended portions being 20 c lapped one upon the other and united by double

lines of stitching, one in front and the other in rear of the usual line of the inside seam, whereby the leg is given a double thickness on the inside, and a smooth unbroken surface, adapting them to be worn in the saddle with com- 25 fort.

3. In a pair of pantaloons or drawers, a leg having the slits or incisions at its lower end, said incised portion consisting of two thick- 30 nesses lapped and united in the manner de- scribed and shown, whereby the formation of a seam at the end of the slit is avoided and increased strength secured.

In testimony whereof I hereunto set my hand, this 28th day of June, 1884, in the presence of 35 two attesting witnesses.

SAMUEL DIGGS BLAKE.
